[57] CLAIM

The ornamental design for a hair dryer, as shown and described.

DESCRIPTION

FIG. 1 is a left side elevational view of a hair dryer showing my new design;

FIG. 2 is a right side elevational view thereof;

FIG. 3 is a front elevational view thereof;

FIG. 4 is a rear elevational view thereof;

FIG. 5 is a top plan view thereof;

FIG. 6 is a bottom plan view thereof.

The cord portion of the design is shown broken away to indicate indeterminate length.

*FIG. 1**FIG. 2**FIG. 3**FIG. 5*FIG. 4

FIG. 6
